UNITED STATES PATENT OFFICE.

THOMAS P. TAYLOR, OF BRIDGEPORT, CONNECTICUT, ASSIGNOR TO THE CANFIELD RUBBER COMPANY, OF SAME PLACE.

DRESS-SHIELD.

SPECIFICATION forming part of Letters Patent No. 355,572, dated January 4, 1887.

Application filed April 21, 1886. Serial No. 199,579. (No model.)

To all whom it may concern:

Be it known that I, THOMAS P. TAYLOR, a citizen of the United States, residing at Bridgeport, in the county of Fairfield and State of Connecticut, have invented certain new and useful Improvements in Dress-Shields; and I do hereby declare the following to be a full, clear, and exact description of the invention, such as will enable others skilled in the art to 10 which it appertains to make and use the same.

My invention relates to the class of devices known as "dress-shields" or "dress-protectors," particularly to that class of shields worn to protect clothing under the arms, and has 15 for its object to provide a dress-shield which may be instantly and without the slightest trouble placed in position for use, as quickly transferred to another article of clothing, which requires no attachment whatever, but holds 20 itself in place, and which cannot possibly roll up or wrinkle in any manner.

With these ends in view I have devised the novel construction of which the following description, in connection with the accompanying 25 drawings, is a specification, numbers being used to indicate the several parts of the device.

Figure 1 is an elevation of my preferred form of carrying my invention into effect, and Figs. 2 and 3 are elevations of forms of my invention in which the details of construction 30 are slightly modified.

The ordinary dress-shields in use require to be attached firmly to the garment ordinarily by stitching. It has therefore been necessary to have a separate pair of shields secured in every dress or article of clothing 35 which it is desired to protect from perspiration, or else to spend considerable time changing the shields when the garment is changed.

40 A still more serious objection to the dress-shields of this class is the great care required in putting on a tight-fitting garment to insure that the shields or protectors are pressed down smoothly; also, the great care 45 required in stitching them in place, there being a constant liability of the stitching tearing out or the threads breaking while in use. Whenever the threads break or the stitching tears out, the shield rolls up in the armpit and 50 affords little, if any, protection to the garment,

except just at the sleeve-seam. I wholly overcome these objections by providing both sides of the shield or protector with a firm but flexible-jointed stay, which is firmly secured at the edges of the shield, will readily conform to the 55 shape of the body and the arm, and which acts to hold both folds at their distended position under all circumstances, and, moreover, while holding the shields firmly in position, permits them to be readily removed and placed in another garment. The stays are ordinarily made 60 of brass or copper wire.

It will be apparent that my invention is equally applicable to all sizes and styles of shields. I have shown it as applied to the ordinary style of dress-shields now upon the 65 market.

1 and 2 indicate the two folds of the shield, the former acting to protect the sleeve of the garment under the arm and the latter the 70 body of the garment under the arm.

3 indicates the stays, which are secured in any manner at the edges of the folds. As stated above, I preferably use wire for this purpose, and secure it in position by folding the edges 75 of the stay over it, as indicated at 4 in the drawings, and either stitching or cementing the fold in place.

In Fig. 1 I have shown the stays as formed of wire, and provided at their ends with eyes 80 5, which lie at such an angle to each other as to permit them to interlock, as is clearly shown in the drawings. I thus join the stays in the two folds together with a loose joint, so that in use the arm may be lifted and moved freely 85 without the slightest inconvenience.

In Fig. 2 the ends of the stays are provided with similar eyes, which are secured together by a suitable cord or link, 6.

In Fig. 3 the stay in the sleeve-fold is provided with spring-coils 7, which permit the stay to yield when the arm is raised, thus lessening the strain upon the material of the shield.

I am aware that dress-shields have been expanded by marginal frames made without joints, and also that aprons have been provided with spring-clasps, and make no claim thereto.

It will of course be understood that the details of my invention may be considerably va- 95 100

ried without departing from the principle thereof.

I claim—

1. The combination, with a dress-shield, of stays 3, secured at the outer edge thereof and provided at their ends with eyes 5, whereby the stays are secured together.

2. The combination, with a dress-shield having the usual folds, of an independent stay secured at the outer edge of each fold, the ends of said stays being provided with eyes 5, which interlock, as shown, whereby said stays are joined together, but move freely in use.

3. The combination, with a dress-shield, of stays secured at the outer edges of the folds, 15 each of said stays having eyes at their ends, whereby they are joined together, and one of said stays having spring-coils 7, which yield when the arm is raised and prevent strain upon the material of the shield. 20

In testimony whereof I affix my signature in presence of two witnesses.

THOMAS P. TAYLOR.
